ELECTRICAL INTERLOCK

Arthur G. Zippler, Philadelphia, Pa.

Application February 26, 1952, Serial No. 273,507

7 Claims. (Cl. 187—50)

1

My invention relates to new and useful electrical interlocks such as are employed in connection with safety gates or doors of elevator shafts to control the operations of an elevator and said safety gates or doors under certain predetermined relative conditions.

One of the objects of my invention is to provide an electrical interlock which may be mounted on either the right hand or left hand side of an elevator shaft entrance, assuming that a person is inside of the shaft and face the entrance, without the necessity of changing or rearranging the interior mechanism.

Another object of this invention is to generally improve the construction of electrical interlocks which will simplify the structural and operational features and adapt them for use of either vertical side of elevator shaft entrances.

A further object of the present invention is to produce an electrical interlock including a box body provided with attaching wings and having vertical knife receiving slots, one at each side of the device, said slots being open towards the outer sides and at the tops for the purpose of guiding a gate knife into operational relation with a switch operating lever and a locking lever, located at one side of the device corresponding to the path of travel of the knife or associated with the respective slot positioned to receive said knife, said locking lever being maintained in a normally locked condition by a spring actuated shaft carrying a lock operating lever cooperating with an elevator car cam to move the locking lever to an unlocked position, and switch means within the box body for opening and closing a circuit according to the position of the car relative to a landing to control the car operating circuit.

With the above and other objects in view this invention consists of the details of construction and combination of elements hereinafter set forth and then designated by the claims.

In order that those skilled in the art to which this invention appertains may understand how to make and use the same I will describe its construction in detail referring by numerals to the accompanying drawings forming a part hereof, in which:

Fig. 1 is a fragmentary perspective view of an elevator safety gate, its frame and a landing illustrating an installation of the electrical interlock at the left hand side of the gate when looking outward from the elevator shaft or well.

Fig. 2 is a similar view showing the electrical interlock installed at the right hand side of the safety gate.

2

Fig. 3 is an enlarged side view of the electrical interlock showing the positions of the operating elements, including a portion of the gate knife, when the safety gate is closed and the elevator car is away from the landing.

Fig. 4 is a similar view with the operating elements in the positions assumed when the car is at a landing and the associated gate is still closed.

Fig. 5 also is a similar view with the car at a landing and its respective gate open.

Fig. 6 is a further enlarged face view of the electrical interlock with the cover and cam roller removed.

Fig. 7 is a vertical sectional view thereof on the line 7—7 of Fig. 6 illustrating the switch means closed.

Fig. 8 is a similar view showing the switch means open, a portion of the operating lever for the locking lever being broken off.

Fig. 9 is an upper end view thereof.

In carrying out my invention as herein embodied 10 represents the electrical interlock which is mounted on a suitable support 11, such as a gate post forming a part of the frame providing an entrance to an elevator shaft or well. By reference to Figs. 1 and 2 it will be apparent that the interlock can be mounted at either the left hand or right hand side of the entrance which is normally closed by a gate 12, or equivalent, vertically slidably mounted in track rails 13, and carrying a knife 14 cooperating with the interlock. Also cooperating with the interlock is a car cam 15 carried by the elevator car 16 represented by the platform or bottom thereof which, under certain conditions is to be stopped at a landing 17 from which the entrance provides a communication with the elevator shaft or well and the car when the latter is approximately level with said landing. It should be obvious that

40 a plurality of entrances to the elevator shaft can be provided, one above another at different landings, at opposite sides of the shaft at the same landing or any other desirable and suitable locations although only one is shown and described herein for purposes of explanation of the invention.

45 The interlock 10 comprises a box body 18, including the usual sides, upper and lower end walls and back while the front is open but normally closed by a lid 19 detachably held in place by suitable fastening devices, such as screws, and the upper and lower wings 20 and 21, respectively, having holes to receive screws or other equivalent attaching means for mounting the apparatus on a support.

50 The back wall of the body at both sides thereof

from the upper end wall to a location adjacent but spaced from the lower end wall is thickened slightly to provide areas of sufficient size to permit the formation of the opposed vertical side slots 22 and 23 open at the top and opposite sides of the apparatus to the exterior thereof. One of these slots is adapted to receive the free end of the gate knife 14 depending upon which side of the entrance or gate the interlock is mounted for operation.

The face of the upper wing 20 at the upper edge thereof is beveled at 24 and 25 directly above the slots and the back of the body is likewise beveled at 26 and 27 at the upper ends of said slots to provide flared mouths or guideways for the slots to insure unobstructed entrance of the knife into either slot should said knife become misaligned, accidentally or through poor fitting of associated parts.

The thickened portions of the back wall may be so fashioned as to produce vertical longitudinal projections 28, Fig. 6, on the interior of the box body, one projection at each side of the body and spaced apart to provide a channel 29 in which a block of insulation material 30 may be mounted.

On the insulation block 30 is a binding post 31 to which is secured a conductor 32, Figs. 1 to 5, projecting through a hole 33, Figs. 7, 8 and 9, in the top end wall of the box body and said hole may be suitably fashioned to receive a connector 34. The binding post 31 is electrically connected to a contact post 35, as by a bonding strip 36.

Another bonding post 37 is also mounted on the insulation block 30 adjacent the lower end of the latter and a conductor 38 which projects through a hole 39 in the bottom end wall of the box body is attached to said binding post 37 and like the hole in the top end wall, the hole 39 may be appropriately fashioned to receive a connector 40. The binding post 37 is also electrically connected with the movable contactor 41, of the switch or circuit maker and breaker 42, by a pigtail or flexible conductor 43.

The switch 42 includes, in addition to the stationary contact post and movable contactor 41, a panel 44 of insulation material to which said movable contactor is resiliently attached by the pegs 45, coil springs 46, washers 47 and cotter pins 48 in a well known or conventional manner. Said switch, especially the insulation panel thereof, is fixed to the contact shaft 49 that is journaled in the side walls of the box body with the ends of said shaft protruding beyond the outer faces of said body side walls. For the purpose of properly positioning the switch, the contact shaft 49 may have a flat 50 intermediate its ends so as to be located substantially midway between the side walls within the body compartment and the panel 44 engages the flat and is fastened in place by securing means 51, such as screws. The contact shaft 49 is urged in a rotational direction, which will normally maintain the movable contactor 41 out of engagement with the contact post 35, by a spring 52, Fig. 6, such as one of the coil type surrounding said shaft with one end attached to the shaft and the other end resting against the interior of the body back wall.

On one protruding end of the contact shaft is detachably mounted a holding means 53, such as a collar, to assist in preventing accidental displacement of said shaft but permitting removal of said shaft when desired. On the other protruding end of the same contact shaft 49 is also detachably mounted a contact lever 54

75 having a flat or square heel 55 at its lower end for coaction, under certain conditions, with the flat or square stop surface 56 on the upper portion of each of the external lugs 57 and 58, one 5 on each side of the box body or on opposite side walls of said body. Said contact lever is so weighted that the switch will open even if the spring 52 accidentally breaks. In addition said contact lever 54 has a toe 59 projecting from the 10 lower portion thereof towards the back of the device and across one of the slots 22, 23. At the upper end of the contact lever 54 is a nose 60 having beveled or canted upper and lower surfaces, Fig. 4, whereby said contact lever, when 15 lying across a slot 22, 23, may be retracted by the knife 14 moving in either direction, it being understood that said contact lever 54 extends upwardly in a generally vertical direction, the same as the switch contactor 41, from the contact shaft 20 49.

25 A lock shaft 61 journaled in the side walls of the body with the ends of said shaft protruding beyond the exterior surfaces of said side wall and, more particularly, the lugs 57, 58 which, 30 by preference, are thicker than or approximately the same thickness as the contact lever 54. The lock shaft may be held against endwise or longitudinal movements by washers 62 and cotter pins 63 on the shaft inside of the body to prevent 35 accidental displacement of said lock shaft, although it can be dismounted.

35 On one protruding end the lock shaft 61, which is below the plane of the bottoms of the slots 22, 23, is detachably mounted a locking lever 64 that extends upwardly along side of the contact 40 lever 54, but free therefrom, and this locking lever has a nose to project across the vertical plane of either of said slots 22, 23. The nose of 45 said locking lever has a beveled or canted upper edge 65 and undercut primary and secondary or safety locking surfaces, 66, 67, respectively, the latter extending beyond the former and in a different or higher plane. The primary locking surface 66 is adapted to engage the upper edge of the knife when the latter is in one of the slots 22, 23, with which the locking lever is associated, while the car is away from the landing, but if for 50 some unexpected reason, such as the knife not fully entering the slot, the secondary locking surface 67 will engage the knife and prevent opening of the gate.

55 The lock shaft 61 is urged in a rotational direction which will normally project the nose of the locking lever 64 across the plane of the slots 22, 23 by a spring 68, preferably of the coiled type, surrounding said lock shaft with one end of the 60 spring fastened to the lock shaft and the other end engaging the inner surface of the back of the body, for example. Also the locking lever 64 is so weighted that it will move to the holding position even if the spring 68 accidentally breaks.

65 On an end of the lock shaft 61, generally the protruding end opposite that on which the locking lever 64 is mounted, although it can be otherwise, 70 is detachably mounted the pendant operating lever 69 for cooperation with the cam 15 on the car 16 and, by preference, a cam roller 70 is mounted on the lower free end of said operating lever to actually engage the cam with a minimum of friction. The cam 15, which is mounted on the car 16, has a straight vertical portion 71 to hold the locking lever in a retracted position, against the action of the spring 68, and outturned upper and lower end guide portions 72.

75 In practice, the electrical interlock is installed

on either the right hand or left hand side of one or each entrance to the elevator shaft, generally being mounted on the frame in which a gate is vertically slidably mounted and the electrical connections are made with a source of power and a contact which makes and breaks the elevator operating power. The electrical current which operates the elevator does not pass through any interlock and where there is a plurality of interlocks, such as those at a number of different landings, said interlocks are wired in series thus when the circuit is broken at one interlock it is, in effect, broken at all interlock locations.

When the interlock is located on the left hand side of the entrance, Fig. 1, the knife 14 is attached to the left hand side of the safety gate 12 and said knife and associated relatively positioned whereby the knife may enter the right hand side slot 23 in the interlock as the gate is moved to the closed position and withdrawn from said slot when the gate is opened. Under such conditions the locking lever and the contact lever are mounted on the right hand ends of their respective shafts and the operating lever 69 is properly mounted on the lock shaft to be engaged by the lock operating cam on the elevator car.

Should it be desirable or necessary to install the interlock on the right hand side of the entrance, Fig. 2, the locking lever and the contact lever are removed from their respective shafts, if they are on the right hand ends, and placed on the left hand ends. It being understood that the shafts can be adjusted lengthwise if necessary but in most instances the contact lever and collar are merely interchanged and usually the locking lever and operating lever are likewise interchanged. In the latter instance though it is possible that the operating lever can be on the same end of the lock shaft as the locking lever. This reversal of the contact and locking levers will place them in association with the left hand side slot 22 and position for cooperation with the knife mounted on the right hand side of the safety gate for movement into and out of said left hand side slot.

Adapting the device for installation on either side of the entrance requires no changes in or substitution of differently styled parts of the apparatus but merely the proper mounting of the contact and locking levers on the appropriate ends of their respective shafts while the elements inside of the box body remain undisturbed. Of course, it must be ascertained that when both the contact and locking levers are retracted, the contactor 41 is also retracted and the operating lever 69 is in a projected position or close to the back wall of the apparatus.

In either instance, when the safety gate is closed the knife 14 will be in one of the slots 22, 23, according to which side of the entrance the interlock is mounted on, for example that depicted in Fig. 3. Assuming that there is no car at the landing, then the spring 68 will urge the lock shaft 61 in a rotational direction to hold the nose of the locking lever 64 across the knife and retain the safety gate in a closed position. At the same time said knife will be in engagement with the toe 59 of the contact lever 54 and hold it in the projected position which maintains the switch 42 closed, Fig. 7, so that the elevator is free to be operated. While the switch is closed, even if the knife is raised slightly, the spring 52 on the contact shaft 49 is not strong enough to overcome the weight of associated

parts and retract the contact lever and open the switch.

When a car approaches and reaches a landing, Fig. 4, the cam 15 engages the operating lever 69, particularly the roller 70, and projects said operating lever towards the back wall of the apparatus. This will retract the locking lever 64 to free the knife and hence the safety gate. Said safety gate may now be raised which will withdraw the knife from the slot in which it has been resting and as said knife is lifted it will engage the underneath beveled edge of the nose of the contact lever 54 to move the latter to a retracted position, Fig. 5, and open the switch 42, Fig. 8, and prevent operation of the elevator car while it is at the landing.

When the gate is again lowered the knife will enter the slot with which said knife is associated, as slot 22, Fig. 4, and engage the toe of the contact lever to project the nose thereof across the vertical plane of the slot and close the switch 42, Fig. 7, after which the car may be operated. As the car moves away from the landing the cam 15 will be carried out of engagement with the operating lever 69 releasing the spring actuated lock shaft so that the nose of the locking lever can be projected across the plane of said slot, as 22, above the knife to hold the latter and thereby prevent opening of the safety gate while the car is away from the landing. During the time the car is between landings or floors at different levels none of the safety gates can be opened and the interlock electrical circuit cannot be broken or opened wherefore the elevator can be operated at will.

If, through some unforeseen reason, the knife is out of its slot and the noses of either or both the contact and locking levers are in a position across the plane of the slot, the gate can be closed because as said gate is moved towards the closed position the knife will engage the beveled upper edges of the noses of either or both of the contact and locking levers and temporarily retract them. As soon as the knife has passed beyond said noses they are in condition to be again projected across the plane of the slot.

From the foregoing it will be apparent that I have produced a relatively simple, compact and inexpensive electrical interlock which is strong and durable and capable of long usage with very little chance of getting out of proper working condition due to wear and tear.

Of course I do not wish to be limited to the exact details of construction herein shown and described as these may be varied within the scope of the appended claims without departing from the spirit of my invention.

Having described my invention, what I claim as new and useful is:

1. An electrical interlock comprising a box body including back, side and upper and lower end walls providing a compartment with an open front normally closed by a detachable cover, said back wall having vertical slots therein at opposite sides thereof and open at the tops and the respective opposite outer sides of the body, said interlock adapted to be mounted on either side of an elevator well entrance whereby one of said slots is adjacent to and facing towards said entrance, such slot adapted to receive a knife carried by a safety gate vertically slidably mounted in said entrance, a lock shaft projecting through the body and journaled in the side walls with the ends of said lock shaft protruding beyond the side walls, a locking lever detachably

mounted on the end of the lock shaft at the same side of the body as the slot with which the knife cooperates, said locking lever having a nose for projection across the vertical plane of the slot to hold the knife therein, means to normally urge the locking lever in a direction to cause its nose to project across the vertical plane of the slot, an operating lever detachably fastened to said lock shaft to be acted upon by means carried by an elevator car to retract the locking lever, a contact shaft projecting through the body and journaled in the side walls with the ends of said contact shaft protruding beyond the side walls, a contact lever detachably mounted on an end of said lock shaft at the same side of the body as the slot with which the knife cooperates, said contact lever having a nose with upper and lower beveled edges and adapted to be projected across the vertical plane of the slot, means as a part of said contact lever to be acted upon by the knife for projecting the contact lever nose across said vertical plane of the slot, said contact lever nose to be retracted by direct action of the knife thereon, an electrical switch within the body compartment and including a contactor on the contact shaft, and a light tensioned spring to normally urge said contact shaft in a rotational direction to maintain the switch opened.

2. The electrical interlock according to claim 1 wherein the upper edge of the nose of the locking lever is beveled.

3. The electrical interlock according to claim 1 wherein the lower edge of the nose of the locking lever is undercut on two different levels.

4. The electrical interlock according to claim 1 wherein the upper edge of the nose of the locking lever is beveled and the lower edge of said nose is undercut on two different levels.

5. The electrical interlock according to claim 1 wherein the front and rear walls of each slot at its upper end are beveled outwardly to provide a flared mouth to each slot.

6. The electrical interlock according to claim 1 wherein the means as a part of the contact lever to be acted upon by the knife is a toe projecting across the vertical plane of the slot adjacent the lower end thereof and wherein said

contact lever has a square heel to the rear thereof, in combination with a lug on either side of the body having a flat upper stop surface to be engaged by the heel of the contact lever as the latter is retracted.

7. An electrical interlock comprising a box body including back, side and upper and lower end walls forming a compartment with an open front closed by a detachable cover, said back wall having vertical slots therein at opposite sides thereof and open at the tops and the respective opposite outer sides of the body, a contact shaft projecting through the body and journaled in the body side walls with the ends of said contact shaft protruding beyond said body sides, a contact lever selectively and detachably mounted on either end of said contact shaft, said contact lever having a nose at the outer end thereof for projection across and retraction from the vertical plane of the slot on the same side of the body as the assembled contact lever and adjacent the upper end of said slot, a toe on the lower part of the contact lever constantly projecting across the vertical plane of the slot adjacent the lower end thereof, a switch within the body including a movable element connected with the contact shaft, means to maintain said switch open when opened, the same being closed and opened by actuation of the contact lever, a lock shaft projecting through the body and journaled in the side walls with the end of said lock shaft protruding beyond said body sides, a locking lever selectively and detachably mounted on either end of said lock shaft and beside the contact lever, said locking lever having a nose for projection across the vertical plane of the same slot as the nose of the locking lever and retraction therefrom, means to normally urge said locking lever in a projected direction, and means on the lock shaft whereby said locking lever may be retracted when said last mentioned means is actuated in opposition to the locking lever projecting means.

ARTHUR G. ZIPPLER.
